UNITED STATES PATENT OFFICE.

HENRY CLAY BASCOM AND ROBERT GALBRAITH, OF LANSINGBURG, NEW YORK, ASSIGNORS TO SAID BASCOM.

DESIGN FOR A DWARF PARLOR-STOVE.

SPECIFICATION forming part of Design No. 21,598, dated May 31, 1892.

Application filed March 7, 1891. Serial No. 384,187. Term of patent 14 years.

To all whom it may concern:

Be it known that we, HENRY CLAY BASCOM and ROBERT GALBRAITH, citizens of the United States, residing at the village of Lansingburg, in the county of Rensselaer and State of New York, have jointly invented and produced a new and original Design for Dwarf Parlor-Stoves, of which the following is a specification, reference being had to the accompanying drawings, in which—

Figure 1 represents a front view of a stove having said new design, and Fig. 2 an end view of the same stove.

One characteristic feature of our said design is the shape or configuration of the stove irrespective of its surface-ornaments, the same comprising the flat base, having the hearth extension *a* and downwardly-inclined border *a'*, with straight front and rear side edges, convexly-curved corners *a*², and end concavities *a*³, the flat top having the rear extension *b* and the downwardly-inclined border *b'*, with a straight front edge, convexly-curved corners *b*², and rear concavity *b*³, the straight upright corners *c* *c'*, the front formed with the forwardly projecting and inclined upper part *d*, having the raised quadrilateral doors

d', the oblong mid-band *e*, and the lower door having the outwardly and convexly inclined upper portion *f*, the concavely-inclined surface *f'*, and the bottom forward extension *f*², and the ends having the upper and lower concavely and convexly curved portions *g* *g'* and the intermediate projecting quadrilateral door *h* or panel *h'*, all disposed together essentially as represented by said drawings.

A further characteristic feature of our said new design consists of right and left foliate scroll vines, as *i* *i'*, and united pairs of right and left foliate scroll vines, as *j* *j'*, shaped and disposed on the front and end of the stove essentially as represented in the aforesaid drawings.

We claim as our invention—

The design for a dwarf parlor-stove, substantially as shown and described.

In testimony whereof we hereunto set our hands, in the presence of two subscribing witnesses, this 4th day of March, 1891.

H. CLAY BASCOM.
ROBERT GALBRAITH.
